DESIGN FOR A WALKING FIGURE TOY

Salvatore Capillo, Ossining, N. Y.

Application August 26, 1946, Serial No. 132,874

Term of patent 14 years

(Cl. D34—15)

To all whom it may concern:

Be it known that I, Salvatore Capillo, a citizen of the United States of America, residing at Ossining, in the county of Westchester and State of New York, have invented a new, original, and ornamental Design for a Walking Figure Toy, of which the following is a specification, reference being had to the accompanying drawings, forming a part thereof, wherein:

Fig. 1 is a top plan view; and

Fig. 2 is a side elevational view of a walking figure toy showing my new design.

The opposite side of the toy is substantially like the side disclosed.

I claim:

The ornamental design for a walking figure toy, as shown and described.

SALVATORE CAPILLO.
